US00D430714S

United States Patent [19]

Song

[11] Patent Number: Des. 430,714

[45] Date of Patent: ** Sep. 5, 2000

[54] ELECTRIC CLEANER LID

[76] Inventor: **Seoung-Wook Song**, 5-103 Kaepo 1-cha Woosung Apt., 503 Daechi 1-dong, Kangnam-gu, Seoul, Rep. of Korea

[**] Term: **14 Years**

[21] Appl. No.: **29/108,802**

[22] Filed: **Aug. 3, 1999**

[51] LOC (7) Cl. **15-05**

[52] U.S. Cl. **D32/25**

[58] Field of Search D32/30, 23, 21, D32/25, 1; 15/326, 323, 320, 321, 327.1, 353, 246.5, 327.2
